ILLUMINATING DEVICE

Maude Adams and Raymond F. Howe, New York,
N. Y., and Perley G. Nutting, Washington, D. C.

Application July 9, 1931, Serial No. 549,660

11 Claims. (Cl. 176—39)

This invention relates to illuminating devices, and with particularity to high powered incandescent lamps.

The invention is in the nature of an improvement upon the type of lamp shown in the patent of Raymond Howe, Patent No. 1,936,762, issued November 28, 1933, and is related to the lamps shown in our Patent No. 1,884,957, issued October 25, 1932.

10 An object of the invention is to provide a novel method of supporting the filament of a high powered incandescent lamp so that the said lamp may be used in a tilted position without danger of the filament or filament supports sagging.

15 Another object of the invention is to provide an incandescent lamp wherein the filament is supported within the lamp from opposite ends thereof, and is at the same time capable of expanding and contracting without causing strain 20 on the lamp wall.

A feature of the invention resides in an improved manner of supporting the filament of an incandescent lamp in the wall or other portion of the lamp envelope.

25 A further feature relates to the novel organization and arrangement of elements which go to make up an efficient high powered incandescent lamp wherein the filament is supported in substantially all directions so as to prevent any appreciable sagging or tilting movement thereof.

30 At the same time the filament is free to expand longitudinally and laterally.

Other features and advantages not specifically 35 enumerated will be apparent after a consideration of the following detail description and the appended claims.

Referring to the drawings:

Fig. 1 shows a high powered incandescent lamp embodying one form of filament support according to the invention;

Fig. 1^a is a detail end view of a portion of the lamp of Fig. 1;

Fig. 2 shows a modified manner of supporting the filament at the upper end thereof;

45 Figs. 3 and 4 show still further modifications of the manner of supporting the incandescent filament at its upper end;

Figs. 5 and 6 are sectional views of the structure of Fig. 4, taken along the lines 5—5 and 6—6 thereof.

Referring more particularly to Fig. 1, there is shown a high powered incandescent lamp of the type disclosed in the application of Raymond Howe, referred to hereinabove, and for the sake

of simplicity, the corresponding parts of the lamp of Fig. 1 and the lamp shown in said Howe application will be designated by the same numerals. The lamp comprises in general an evacuated envelope 1, which may be bulb-shaped, cylindrical-shaped, or any other shape desired. This envelope may, although not necessarily, contain a filling of an inert gas such as nitrogen or the like. The incandescent member 2 may be in the form of a closely coiled tungsten wire comprising six separate sections disposed parallel to each other in substantially the same plane, and with the said sections connected in series. Attached to the constricted end 3 of the envelope 1 is a reentrant portion 4 which carries integral therewith the seal-in supports 5 and 6 through which pass the metallic rods 9 and 10, it being understood that the said rods are hermetically sealed into the supports 5 and 6. While the drawings show a single pair of supports 5 and 6 and 20 associated rods 9 and 10, it will be understood that these supports and rods may be arranged in pairs to provide a frame as disclosed in the said Howe application. Preferably, also the rods 9 are of a heat resisting material such as tungsten or the like, and have the same coefficient of expansion as the members 5 and 6 so that a single rod of the same material may be employed as a lead-in and as the support.

As described in detail in said Howe application the supports 9 and 10 at their upper ends are bent at right angles and are rigidly attached to an insulation cross piece 15 which may be in the form of a long narrow block of zirconia or other heat-resisting insulating material. A similar block of insulation 32 is supported transversely below the block 15 from the supports 9 and 10. Passing through the upper insulation support 15 is a pair of filament hooks 29, these hooks being preferably of the type disclosed in 40 said Howe application, and being provided at their lower ends with hook portions 30 to receive and support the upper ends of the filament coils. The lower ends of the filament coils are prevented from tilting by means of hook members 35 which 45 are fastened in any suitable manner to the block 32 and are provided with looped portions 36 and 37 so as to freely receive the lower ends of the filament coils as described in detail in said Howe application. The electrical ends of the filament coils are welded or otherwise fastened respectively to the supports 9 and 10 so as to enable the heating current to be passed through the filament when the lamp is connected in circuit. If desired, an additional cross piece of insulation 50

intermediate the members 15 and 32 may be provided to support the filament at its central portion, as disclosed in Howe application, Serial No. 543,034, filed June 9, 1931.

8 The above described arrangement has been found to provide a satisfactory means for supporting the filament 2 against sagging when said filament is heated to incandescence. Furthermore, the particular manner of supporting and 10 anchoring the filament enables the filament to expand longitudinally and laterally without exerting any excessive strains upon either the insulators 15, 32, or the supports 8 and 16. However, it has been found that in very high powered lamps of the type disclosed, for example in a lamp of from 1 k. w. to 30 k. w., the heat of the filament when the lamp is running and the weight thereof are so great as to considerably limit the angle at which the lamp can be used. In many 15 instances it is highly desirable to use the lamp in a tilted position and even in a horizontal position. Accordingly, the structure shown in Fig. 1 may be provided with a member 60 which is fastened into the constricted portion or tubulation 25 61 of the lamp envelope 1. The member 60 is preferably provided with projections 62 so as to increase the hold or seal between the said member 60 and the glass of the tubulation 61. The member 60 terminates at its lower end in a portion 63, 30 the side members 64 and 65 of which loosely pass through corresponding holes in the insulator 15. However, the opening in the portion 63 is of materially greater size than the thickness of the insulator 15, so that the said insulator is capable 35 of movement in an up and down direction relatively to the member 60. Since the member 60 is rigidly sealed into the portion 61 of the envelope the said member 60 prevents the insulator 15 from tilting with respect to the longitudinal 40 axis of the lamp. Consequently since the filament is supported from the insulator 15, the lamp as a whole may be used in any position, even in a horizontal position, without danger of the filament assembly sagging or tilting. There is thus 45 provided a lamp structure wherein a heavy filament may be used and operated at high temperatures without danger of the filament sagging, short-circuiting, breaking, etc., when the lamp is used in a non-vertical position. While the drawings show the member 60 as flat, this member 50 may be round or any other desired shape in cross-section.

The manner of assembling the lamp shown in Fig. 1 will follow ordinary lamp practice, in which 55 case the portion 61, if desired, may correspond to the well known exhaust tubulation and after the exhaustion of the lamp is completed, the said tubulation 61 may be heated and sealed off and at the same time pressed against the support 60. However, instead of exhausting the lamp 60 from the tubulation 61, the lamp may be provided with an exhaust tubulation at the portion 4 thereof, as is well known in so-called tipless lamps, in which case the portion 61 will 65 simply be a closed portion of the lamp envelope of constricted diameter to receive the member 60 which may be pressed, swaged, or otherwise sealed into the glass.

Referring to Fig. 2 there is shown a slightly 70 different modification of the structure shown in Fig. 1. In this figure the incandescent filament and the insulator supports, as well as the lead-in supports for the filament may be the same as the corresponding parts shown in Fig. 1. In this figure, however, the member 60 is not sealed into

the constricted portion 61 of the envelope 1. The said constricted portion is hollow except at the point 65 where the lamp may be sealed off. Therefore, the member 60 is free to slide in the portion 61 and at the same time, due to the engagement of the member 60 with the walls of the portion 61, the said member acts as a brace to support the filament assembly as above described in connection with Fig. 1. In this modification, however, the expansions and contractions of the 10 filament are not transmitted through the member 60 to the glass of the envelope, and the filament is, therefore, free to expand without any danger of breaking the glass of the envelope. 15

In Fig. 3 there is shown a still further modification along the lines of the modification shown in Fig. 2. In this figure the member 60 may be made in the form of a square or round bar which is adapted to telescope with a corresponding hollow member 66. A spring 67 is seated within 20 the member 66 and provides a resilient connection between the said members 60 and 67. Therefore, as the filament assembly expands and contracts there is no danger of the member 60 expanding sufficiently to break the glass 65, since 25 the pressure is taken up by the spring 67. It will be understood, of course, that the arrangement shown in Fig. 3 is merely schematic and that any equivalent manner of providing a resilient connection between the members 60 and 30 66 may be employed, so long as the said members provide sufficient lateral rigidity to prevent the filament assembly sagging.

Referring to Figs. 4, 5 and 6, there is shown a preferred manner of supporting the filament assembly. In these figures the filament assembly may be the same as that disclosed in connection with Figs. 1 to 3, and therefore corresponding parts are designated by the same numerals. In these figures the filament assembly is supported 40 at its upper end by means of a brace structure comprising a pair of metal strip members 68 and 69. Each of these members passes around the insulator bar 15, preferably, although not necessarily, in the manner shown in Fig. 6, and if desired the said members can be welded or otherwise rigidly fastened to said insulating bar. The upwardly extending legs of the members 68 and 69 are welded or otherwise fastened to a rectangular shaped ring member 70, as shown more 50 clearly in Fig. 5. The member 70 is adapted to enter a correspondingly shaped constricted portion 71 of the lamp envelope, it being understood that sufficient clearance is left between the upper end of the brace and the wall of the envelope to allow for the maximum expanding 55 movement of the filament. This arrangement therefore provides a relatively simple and strong support for the filament assembly, and there is very little likelihood of the said assembly sagging when the lamp is used in a non-vertical 60 position.

The members 60 of Figs. 1, 2 and 3 and the members 68, 69, 70 are preferably made out of a heat resistant material such as tungsten or the like.

While specific ways of supporting the upper end of the filament assembly with relation to the glass envelope are shown in the figures of the drawings, it will be understood that the invention 70 is not limited thereto, the invention broadly consisting in the idea of providing an incandescent lamp with means for supporting a relatively heavy filament assembly at both ends of the lamp and interiorly thereof, the support at one end 75

being freely movable with respect to the longitudinal axis of the lamp so as to allow for expanding of the heated parts without placing any undue strain upon the glasswork of the lamp.

5 Furthermore, while a coiled filament lamp is shown, any other type of filament may be employed such as a ribbon filament, a looped filament, etc.

10 Other modifications and changes may be made in the structures disclosed in the drawings without departing from the spirit and scope of the invention.

15 For example instead of employing a single rod 60 for supporting the filament assembly against sagging, two or more rods may be employed as shown in Fig. 2^a. Furthermore, instead of employing the specific structure comprising the members 63, 64 and 65 for anchoring the rod, the said rods may be merely provided with lateral 20 projections 60a, 60b, as shown in Fig. 2^a to prevent their becoming dislodged from the insulator 15.

25 In the case of extremely high powered lamps it may happen that the supporting member or members 60 will after a time reach a higher temperature than the constricted portion 61 of the envelope. In order therefore to protect the gas at this portion of the envelope from the heat of the member 60, the said member or members may 30 be provided with an insulating wrapping such as asbestos or the like. Or if desired, the said members 60 may be provided with resilient metallic members such as coiled or leaf springs for limiting the area of contact with the glass of the envelope. Thus there is shown in Fig. 2^b one of the 35 members 60 so as to attach thereto at its upper end a coiled spring 60c. This spring 60c may be of gradually increasing diameter so that only one, or a few turns thereof actually come into contact 40 with the glass 61. Instead of using a coiled spring, one or more leaf springs may be attached to the member 60 to limit the area of contact with the glass, or if desired, the member 60 itself may be provided with a corrugated surface or even with 45 points, so as to limit the area of contact with the glass without affecting the rigidity of the support.

50 If springs such as 60c are employed the said springs are preferably made out of high heat resisting material such as nichrome, molybdenum or the like.

What is claimed is:

55 1. A lamp comprising an evacuated envelope, a frame structure including a pair of metallic uprights arising from one end of said envelope, a pair of insulation cross pieces supported between said uprights, an incandescent member supported from said cross pieces, and means at the opposite end of the envelope to support said frame structure against lateral displacement 60 while permitting longitudinal expansion and contraction of the incandescent member.

65 2. A lamp according to claim 1 in which the said means supported from the said opposite end of said envelope slidably engages one of said cross pieces.

3. A lamp according to claim 1 in which the said means supported from the said opposite end

of the envelope is provided with a looped portion surrounding the upper cross piece.

4. A lamp comprising an evacuated envelope, a filament assembly, said assembly being supported at one end of said envelope, the other end of said envelope having a constricted portion, a hollow tubular member adapted to fit within said constricted portion, for longitudinal movement therein, but held against lateral movement, and a rigid connection between said member and said filament assembly for supporting said assembly against tilting when the lamp is used in a non- 10 vertical position.

5. A lamp according to claim 4 in which said member is provided with a pair of spaced arms 15 engaging said filament assembly.

6. A lamp comprising an evacuated envelope, a plural coiled filament, a metal frame arising from one end of said envelope, said frame supporting at its upper ends a transverse strip of insulation from which the filament coils are suspended, a substantially rigid rod supported by said strip and projecting into a constricted portion at the opposite end of said envelope to prevent said filament sagging when the lamp is used 25 in a non-vertical position while permitting longitudinal expansion and contraction of the filament coils.

7. A lamp according to claim 6 in which the said rod fits slidably within the constricted portion of the envelope.

8. A lamp according to claim 6 in which said rod is surrounded at its upper end with means for protecting the glass of the envelope from the heat of said rod.

9. A lamp according to claim 6 in which said lamp is surrounded at its upper end with a resilient member for limiting the area of contact with the glass of said constricted portion.

10. A lamp comprising a heavy coil filament, an 40 evacuated envelope in which said filament is mounted, means for substantially rigidly supporting said filament at one end of said envelope and means for substantially rigidly supporting said filament at the other end of said envelope, the 45 last mentioned means including a tubular metallic member attached to the filament assembly and a constricted portion of said envelope corresponding in shape to said tubular member and in which said tubular member is received for longitudinal movement therein.

11. A lamp comprising an evacuated envelope, a heavy luminescent member formed in sections disposed in parallel relation within said envelope, rigid means for supporting said member from 55 one end of said envelope, and rigid movable means for supporting the other end of said member from the opposite end of said envelope, said means being movable in a direction longitudinal of said sections and rigid in a lateral direction, whereby 60 the luminescent member is prevented from sagging when the lamp is placed in a horizontal position.

MAUDE ADAMS.
